UNITED STATES PATENT OFFICE.

RAGNAR A. ROSSOE, OF CHICAGO, ILLINOIS, ASSIGNOR TO U. S. PRODUCTS CORPORATION, OF CHICAGO, ILLINOIS, A CORPORATION OF ILLINOIS.

FAN.

1,384,155.

Specification of Letters Patent. Patented July 12, 1921.

Application filed January 2, 1918. Serial No. 209,857.

To all whom it may concern:

Be it known that I, RAGNAR A. ROSSOE, a citizen of the United States, residing at Chicago, in the county of Cook and State 5 of Illinois, have invented a certain new and useful Improvement in Fans, of which the following is a full, clear, concise, and exact description, reference being had to the accompanying drawings, forming a part of 10 this specification.

My invention relates to fans.

I have found that the fans constructed for use in connection with automobile radiators are highly inefficient, poorly designed 15 and excessive in weight and cost.

The result is that radiators, even if of good design, do not develop the proper capacity and cause overheating of the cooling medium.

20 The object of my invention is to provide an improved fan of high efficiency, low in cost of construction and strong and dependable in mechanical structure.

I do not intend to limit my invention to 25 fans for automobiles, but consider that the improvements which I have outlined may be applicable in other relations.

In the patent to Halvorsen No. 1,031,545, granted July 2nd 1912, there are disclosed 30 the principles involved in the construction of a screw propeller of high efficiency. I have adapted the principles therein formulated to the use of propelling air,—that is, the design of the fan.

35 In the accompanying drawings I have illustrated my invention as applied to a radiator fan for a well known type of automobile.

It is well known that in this particular 40 type of automobile the capacity of the radiator is insufficient to keep the engine cool, particularly when the same is operating on heavy load at relatively low speed.

In the accompanying drawings—

45 Figure 1 is a front elevation of a fan constructed in accordance with my invention;

Fig. 2 is a side elevation of the same;

Fig. 3 is an elevation of one section of the fan;

50 Fig. 4 is a fragmentary cross section illustrating the manner of attaching one section to an adjacent section;

Fig. 5 is an exploded view of the pulley and bushings;

55 Fig. 6 is a sectional view taken on line

6—6 of Fig. 1 showing the pulley members, fan hubs, and bushings in assembled form;

Fig. 7 is a sectional view of a modified form of my fan;

Fig. 8 is a sectional view of the above 60 form adapted for the reception of ball bearings; and

Fig. 9 is a fragmentary detail section of a modified construction of the above.

I construct the fan shown in the drawings 65 from sheet metal. The fan consists of a plurality of sections which are jointed together, as will be described later. These sections are stamped from flat metal in the outline shown in general in Fig. 3 by means of the 70 dotted lines 1. The section comprises a fan portion 2 and a hub portion 3, this hub portion having a rearwardly projecting portion 4 which becomes flanged for attaching to the driving pulley 5. 75

After the section is blanked out, the hub portion 3 is formed as is shown in full lines in Fig. 3 and also as shown in Fig. 4. This hub portion is formed into a section of a cylinder as shown at 6 with a flange 7 at the 80 rear edge of the same. This forming is preferably done by stamping at a single operation. An attaching portion 8 extends from the edge of the cylindrical hub portion 6 and is adapted to be joined to the 85 blade portion of the adjacent section, as by means of the rivets 9 (see Fig. 4).

After the hub portion has been formed, the blade portion 2 is stamped or formed into the curvature shown in Figs. 1 and 2. 90 As previously explained, the blade is formed according to the principle set out in the above mentioned Halvorsen patent.

When the sections have been secured together to form a complete fan, the pulley 5 is attached to the flanges 7 which are trimmed to a circular or arcuate formation. The pulley 5 comprises a pair of flanged cup members 10—10 placed back to back so that the bottoms 11 of the cups form 100 the web of the pulley. The flanges 12 serve to guide the belt and prevent it from running off the pulley.

As shown in section in Fig. 6, the flange 7 of the hub portion of each section is attached to the web of the pulley 5 by means of rivets 13 which extend through the web of the pulley and through the flange 14 of a collar 15 that is placed upon the other side of the web.

The structure thus far described forms a light but very strong fan and pulley structure. This structure is provided with bearings by means of the bearing bushings 16 and 17 which are introduced into opposite ends 5 of the bore of the fan and pulley structure above described. The bushing 17 is of a length such that it extends through the flange collar 15 and through the bore of 10 the web of the pulley 11 into the bore of the cylindrical hub formed by the curved portion 6. The bushing 16 extends into the bore formed by the curved portion 6 and thus the two bushings 16 and 17 are brought 15 into alinement very readily.

In the modified embodiment illustrated in Fig. 7 I attach the fan sections together by welding and equip the fan with a crowned pulley formed of a single piece of 20 metal. In this form the rear portion 4' of each fan section is made considerably longer than in the previous embodiment to enable these portions to extend entirely through the pulley to support the same and for attaching 25 to the web of the pulley, this web being on the side of the pulley farthest from the fan. The fan sections are blocked out with the outer edge 20 of the rear portion 4' inclined slightly toward the axis of the 30 fan as shown. The sections are assembled as previously described with the exception that the attaching portions 8' are spot welded to the blades 2' at the points 21 rather than riveted. The succeeding step is to cut flat 35 faces 22 on the inclined edges 20 of all four sections by one simultaneous operation of a circular die. This assures that the annular seat for the edge of the crowned pulley 5' afforded by these flat faces 22 will be 40 concentric with the axis of the fan. The blanks are recessed as shown at 23 so that the above die operation will leave a clean 45 cut.

The pulley 5' is formed with the marginal flanges 24-25, being crowned between these 45 flanges to secure more effective belt contact. The rear flange is shaped back upon itself to form the web 26 of the pulley. The resulting pulley is of cup-shape with open and 50 closed ends. In mounted position the open edge of the pulley 5' bears upon and is rigidly supported by the flat faces 22 of the rear portions 4'. These four rear portions 4' constitute longitudinal webs for radially 55 bracing the open end of the pulley 5'. The radial web 26 of the pulley is spot welded (or riveted) at the points 27-27 to the flanges 7' of each of the fan sections.

In Fig. 8 I have shown the type of fan 60 just described adapted for the reception of ball bearings 30-31. The fan sections are formed and assembled in substantially the same manner as described with the exception that in this embodiment the edges 20 65 of the rear portions 4' are illustrated as cut

parallel to the axis of the fan, the faces 22 projecting slightly above these edges for receiving and supporting the open end of the cup shaped pulley 5'.

A sleeve 32 fits into the hub of the assembled fan for alining the outer races 33-34 of the ball bearings. This sleeve is desirable though not essential for this purpose.

The rear race 33 has a flange 33' at the 75 rear edge thereof which bears against the web 26 extending between it and the end of the sleeve 32. The flange 34' of the front race seats in an annular recess 32' formed in the front end of the sleeve 32. The inner races 35-36 are mounted on the spindle 37, and have fabric oil retaining rings 38 thereon which engage the outer races and seal the ends of the bearings against leakage of lubricating oil from the interior of 85 the sleeve 32. This oil is admitted through the oil cup 38 which also functions as a key to rigidly secure the fan to the sleeve 32. A nut 42 threads upon the front end of the spindle 37 for adjusting the inner races of 90 the bearings and is keyed or pinned to the spindle in any suitable manner. The ball bearings are designed for assuming both the radial and thrust loads of the fan. A hub cap 39 seats in the recess 32', being 95 retained therein by a small split ring 40 engaging in an annular groove in the recess 32'.

Instead of recessing the end of the sleeve 32 it may be given an annular offset 41 as 100 shown in Fig. 9, for receiving the flanged end of the outer race 34 and the hub cap 39.

I find the practice of spot welding the fan sections and pulley together more expeditious than riveting inasmuch as the 105 labor involved in cutting the rivet holes is avoided. Moreover the welded fan is equally as strong as the riveted fan and neater in appearance. It will be apparent that the riveted form of fan illustrated in Figs. 110 1 to 6 is also adaptable to the provision of ball bearings in much the same manner as just described in connection with the welded fan.

I have made tests comparing the efficiency 115 of the fan constructed as above described with the standard fan employed on a well known make of car and I find that the efficiency under various conditions is higher from 40 to 100 per cent. than that of the 120 fan furnished with the vehicle.

I do not intend to be limited to the precise details of construction shown and described.

I claim:

1. In a fan, a plurality of sections, each comprising a segmental hub portion lying in a substantially circumferential plane, an integral blade portion lying in a radial plane, an attaching portion, the attaching portions 130

of the sections being connected to the respective blade portions of adjacent sections.

2. In a fan, a plurality of sections each comprising a blade portion, a hub portion extending normally to the blade portion and an attaching portion and means for securing the sections together with the attaching portions of one section rigidly connected to the blade portion of another section.
- 10 3. In a fan, the combination with, a plurality of sections, each section comprising a blade portion and a hub portion, said hub portion extending axially from the blade portion, said extension comprising a radial flange, of a radial plate for connecting said radial flanges together.
- 15 4. In combination, a plurality of fan sections, each comprising an integral blade, a hub portion, said hub portion comprising a radial flange, and a pulley having a radial attaching plate for attaching the same to the radial flange of each hub portion.
- 20 5. In combination, a plurality of fan sections, each comprising an integral blade and hub portion, said hub portion comprising a radial flange and having a tubular bore, a pulley comprising a pair of cup-shaped members placed back to back to form a central radial web, a flanged collar for engaging one side of said web, said flanged hub sections being attached to the other side of the web and a bushing projecting through the collar and through the pulley into said tubular bore.
- 25 35 6. In combination, a plurality of fan sections, each comprising an integral blade portion and a hub portion, said hub portion comprising a tubular bore and having a radial flange, a pulley having a radial attaching face for attaching to the radial flange of each hub portion and a bushing projecting through the pulley and into the tubular bore of the hub portion.
- 40 7. In combination, a plurality of fan sections each comprising an integral blade, a hub portion, and a radial flange on said hub portion, said sections being attached together, a pulley having a radial web at one edge thereof, the hub portions of said fan sections extending through said pulley and the radial flanges being attached to the radial web of said pulley.
- 45 8. In combination, a fan comprising a plurality of fan sections each having a blade portion, a hub portion and a segmental flange on said hub portion, a pulley for said fan, said pulley having its web or spider at one edge thereof, the hub portions of said

fan sections extending through said pulley, said segmental flanges being attached to the web of said pulley.

9. In combination, a fan comprising a plurality of fan sections each having an integral blade and hub-portion, said hub portion having a radial flange and a longitudinal web, and a pulley having a radial web at one edge thereof for attaching to the radial flanges of each hub portion, the other edge of said pulley being supported by the longitudinal webs on said portions.

10. In combination, a fan comprising a plurality of fan sections each having a blade portion, a hub portion, an attaching portion, and a segmental flange on one end of said hub portion, said sections being secured together by connection between said attaching and blade portions, a pulley for said fan, said pulley being formed of one piece of metal and having a crowned periphery, a web or spider at one edge of said pulley and integral therewith, said hub portions extending axially through said pulley, said segmental flanges being attached to said web or spider.

11. In combination, a fan comprising a plurality of fan sections, each having a blade portion, a hub portion, and a radial flange on said hub portion, a pulley having its web secured to the radial flanges of said fan sections, a sleeve within said hub portions, a spindle within said sleeve and anti-friction bearings between said sleeve and said spindle.

12. In combination, a fan comprising a plurality of fan sections each having a blade portion, a hub portion, and a radial flange on said hub portion, a pulley having its web secured to the radial flanges of said fan section, a sleeve within said hub portions, means for keying said sleeve and said hub portions together, a spindle within said sleeve, ball bearings between said sleeve and said spindle, a cap member seated in the end of said sleeve, and a retaining ring for said cap member engaging in a groove in the end of said sleeve.

13. In combination, a fan composed of a plurality of fan sections, radial segments on each of said fan sections, and an integral pulley comprising a pulley face, flanges, and a radial web or spider, said web or spider being secured to said radial segments.

In witness whereof I hereunto subscribe my name this 21st day of December, A. D. 1917.

RAGNAR A. ROSSOE.
